UNITED STATES PATENT OFFICE

GEORGE A. COTE, OF SPRINGFIELD, MASSACHUSETTS, ASSIGNOR OF ONE-HALF TO
LERGY A. LIVELY

BEDSTEAD

Application filed December 17, 1931. Serial No. 551,593.

This invention relates to improvements in bedsteads and is directed more particularly to improvements in apparatus associated with beds for holding coverings such as blankets and the like.

According to the novel objects of the invention, there is provided in association with a bedstead, an apparatus for holding and supporting the coverings for the bed, such as blankets and the like.

According to the preferred form of the invention, the apparatus includes a frame which is pivoted at one end of the bedstead, as for instance the head, so that it may swing between a position where it overlies the bedstead and an upright position. The frame is adapted to hold and support the covering in such a way that the covering may be moved between a position overlying the bed and another more upright position so as to remove the covering from the bed.

By means of the apparatus of the invention, one or more coverings such as blankets, quilts, or the like, are suitably held in place, while the frame is on the bed; while when the frame is swung away from the bed the covering is suspended thereby. This makes it possible to readily remove the coverings for the purpose of airing the bed; while at the same time the coverings are properly on the bed as is desired.

Various and numerous novel features and advantages of the invention will be more fully herein after referred to in connection with the accompanying drawing, wherein:

Fig. 1 is a small scale side elevational view of a bedstead having the apparatus of the invention associated therewith.

Fig. 2 is an end elevational view of the bedstead shown in Fig. 1 with parts broken away for clearness.

Fig. 3 is an end elevational view of a clip device for engaging an end of a bed covering.

Fig. 4 is a fragmentary plan view of the head end of the bedstead showing certain features of the invention associated therewith.

Fig. 5 is an enlarged fragmentary end elevational view of the apparatus of the invention at the foot end of the bed; and

Fig. 6 is a sectional view through the foot

board of the bed showing a releasable lock associated therewith.

Referring now to the drawing more in detail the invention will be fully described.

In Fig. 1 there is shown a bedstead which has a head 4 and a foot 5 which are connected in the usual way by side rails 6 of usual form. A frame of the invention is associated with the bedstead and has side bars 8 which rest on the rails 6. The frame is pivoted to the rails 6 adjacent the head 4 so that it may swing from the position shown in Fig. 1 to a more upright position.

The side frames 8, at their ends remote from the head 2, are connected to upwardly extending end portions 10, at the foot of the bed, which are connected as shown diagrammatically in Fig. 10 by an end bar 12. A lower clasp bar 14 between the end portions 10 carries clips or clasps 16 shown in Figs. 2 and 3. The bar 14 is adjustable up and down with respect to the members 10.

A spring and mattress may be supported by and between the rails 6 and the side members 8 in conjunction with the end member 12 and are arranged to surround the same, while a covering or coverings, such as 20 may overlie the same, as shown in Fig. 1. The end of the covering at the foot may be secured to the end part of the frame as will appear. As the frame is swung upwardly from the position in Fig. 1, the covering is carried upwardly thereby and suspended by the clasps to be described and associated with the outer end of the frame.

Bearings or brackets such as 22 are carried by the side rails 6 adjacent the head 4 and in these is pivoted a head end bar 24 of the frame which is connected to the side portions 8 thereof. A collar 30 receives one end of a spring 22 coiled about the bar 24, while the other end of the spring may engage the bracket 22 at the left. This spring alone or in conjunction with another spring serves to cushion the action of the frame as it is lowered onto the frame and as it swings to its upright position. It is desired that the frame be cushioned as it approaches the end of its elevating movement so that it will not bring up too sharply against the head. At the same

time it is desired that the spring function to assist in the raising of the frame. This can all be accomplished by the selection of proper springs.

5 The end portions 10 of the frame and end cross bars 12 may be integral, or as shown in Fig. 5, the members 10 and 12 may be tubular in form to receive connections in the form of elbows 4 for connecting them together in a 10 rigid manner. The bar 14 may also be tubular in form and according to the preferred form of the invention, the member 10 at the left is provided with a longitudinally extending slot 42 which receives projections 44 at 15 the end of the tube 14 so as to prevent turning of the tube and so that it may be moved upwardly or downwardly as may be desired.

A bearing member 44 is movable in a plug 46 within the member 14 and a spring 48 between the plug and member 46 urges the member 44 forwardly so that it yieldingly bears 20 against the member 10 at the right. In this way the bar 14 is yieldingly held against shifting movements and may be pulled up or down 25 to various positions of adjustment. The clips or clasps 16 such as shown in Fig. 3 may consist of pivoted members 50 and 52, which have upper ends 54 extending inwardly so as to be adapted to receive therebetween a 30 blanket or the like. Ears 56 and 58 carried by the members 50 and 52 are arranged to swing about a pivot member such as 14. A spring 60 is coiled about the pivot and has its ends 61 and 63 embraced by inwardly extending 35 lugs 51 and 53 of the members 50 and 52. The spring tends to move the members 50 and 52 together so that they yieldingly clasp a 40 blanket or the like.

As stated, the bar 14 may serve as the pivot for the members 50 and 52 of the clips in which case the clips may be moved on the bar. If desired, the clip members may be joined 45 together by separate pivots which may be provided in addition to the bar 14, and the clips may be movable in any convenient manner on the bar 14.

As a blanket or the like is laid over the mattress on the bed the end portion nearest the foot of the bed is dropped over the bar 12 so 50 that the marginal edge portion may be engaged by the clips 16. In this way, as the frame is swung upwardly, the covering is elevated by the frame and cannot become detached therefrom by reason of the clips.

55 As another feature of the invention, clamps 70 may be carried by each of the elbows 40, one of which is shown more clearly in Fig. 5. These clamps may consist of round wire-like members pivoted at 72 to the elbows and have cam ends 73 which bear against spring members 74 within suitable slots of the elbows. The springs 74 are held in the slots by end portions 76 inserted in suitable apertures provided in the slots and they are curved or formed in such a manner

that their upper ends bear on the slots so as to be yieldable. The outer ends of the hooks 70 are turned upon themselves so as to provide restricted throats 80 for yieldingly receiving a blanket or the like.

70 The hooks or clamps 70 are adapted to be moved from the horizontal position shown in Fig. 5 to a vertical position where the outer ends of the clamps abut the members 10. When in this later vertical position the 75 corner portions of the covering may be slipped within the throats of the clamps. The clamps then tend to hold the corner portions of the covering against the mattress. When it is desired to elevate the frame, the 80 clamps 70 may be thrown outwardly and upwardly to a horizontal position so that the covering will not be caught as the frame is elevated. It may be desired to lock the frame in its lower position on the bed and this may be accomplished by means of a spring-like member 80 as shown more clearly in Fig. 6, which is carried by the foot 5 and arranged to be depressed by the frame as it is lowered onto the bed when it will snap over the bar 12, 85

90 It will be observed that a cover or covers are secured to the frame adjacent the foot of the bed and that the frame is movable from its horizontal position on the bed to a more vertical position so as to carry with it the 95 cover or covers. In this more or less vertical position the covers are suspended and held in a flat condition so that the covering may be aired. When the frame rests on the bed the covering is properly positioned and held 100 against accidental displacement. This is all to the end that in making up the bed the covering is held securely in place and is not likely to become mussed up as in the case when the covering is thrown back over the 105 bed in a haphazard way.

Various changes may be made in the construction of the apparatus without departing from the spirit and scope of the invention. I therefore desire to be limited by the 110 following claims rather than by the foregoing description.

What I claim is:

1. A bedstead having foot and head members connected by side rails in combination with an apparatus of the class described comprising, a frame having parallel side bars for resting on said side rails connected to a cross bar adjacent said head member; means by which the cross-bar is pivoted to said bedstead, whereby the frame may swing from a position on said bed to an upright position, and vertical pieces on the outer ends of said side bars connected to an end bar, a second end bar adjustable up and down between said 120 end pieces and clasps on said second bar.

125 2. A bedstead having foot and head members connected by side rails in combination with an apparatus of the class described comprising, a frame having parallel side bars for 130

resting on said side rails connected to a cross bar adjacent said head member, means by which the cross-bars is pivoted to said bedstead, whereby the frame may swing from a position on said bed to an upright position, vertical end pieces on the outer ends of said side bars connected to an end bar, a second end bar adjustable up and down between said end pieces and clasps on said second bar for yieldingly engaging a covering on said bedstead associated with said end pieces.

3. A bedstead having foot and head members connected by side rails in combination with an apparatus of the class described comprising, a frame having parallel side bars for resting on said side rails connected to a cross bar adjacent said head member, means by which the cross-bar is pivoted to said bedstead, whereby the frame may swing from a position on said bed to an upright position, vertical end pieces on the outer ends of said side bars connected to an end bar, a second end bar adjustable up and down between said end pieces and clasps on said second bar for yieldingly engaging a covering on said bedstead associated with said end pieces and a spring device for cushioning the movements of said frame.

30 In testimony whereof I affix my signature.

GEORGE A. COTE.
